UNITED STATES PATENT OFFICE.

ARTHUR E. SHAW, OF PHILADELPHIA, PENNSYLVANIA.

DESIGN FOR A STREET-LAMP.

SPECIFICATION forming part of Design No. 25,976, dated August 25, 1896.

Application filed June 22, 1896. Serial No. 596,547. Term of patent 14 years.

To all whom it may concern:

Be it known that I, ARTHUR E. SHAW, a citizen of the United States, residing in the city and county of Philadelphia and State of Pennsylvania, have invented and produced a new and original Design for Street-Lamps, of which the following is a specification, reference being had to the accompanying drawing, which shows the design.

10 My invention relates to a design for street-lamps, and comprises a base having a socket adapted to fit upon the upper end of the lamp-post, an intermediate box-shaped body in which the burner is located, an upper concavo-convex or dome-shaped part forming the top of the intermediate body, and a ventilating cap or chimney surmounting the dome.

15 My design will be better understood by reference to the annexed drawing, in which is shown a perspective view of my improved street-lamp.

A is the base, having a socket to fit upon the top of the post and laterally-extending supports B to receive the body C. Upon the

base A is arranged the intermediate body C, 25 which consists of a box-shaped frame D. The sides of this box-shaped body are substantially trapezoidal in configuration. Supported above the body C and resting upon it is a dome-shaped part G, forming the top of 30 the body. Surmounting this dome-shaped part G is the ventilating-cap H, and this is formed of a tubular part I, having apertures J at the upper end, an overhanging hood K, and an ornamental figure, such as an eagle 35 L, at the top.

Having now described my invention, what I claim as new, and desire to secure by Letters Patent, is—

The design for street-lamps, substantially 40 as herein described and shown.

In testimony whereof I have hereunto set my hand this 20th day of June, 1896.

ARTHUR E. SHAW.
